(57) CLAIM

The ornamental design for an oil funnel, as shown and described.

DESCRIPTION

FIG. 1 is the first perspective view of our new design;

FIG. 2 is the second perspective view thereof;

FIG. 3 is the third perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the drawings depict portions of the oil funnel and form no part of the claimed design.
